US0D1064500S

(12) United States Design Patent (10) Patent No.: US D1,064,500 S
(45) Date of Patent: * Mar. 4, 2025

(54) GARMENT

(71) Applicant: LULULEMON ATHLETICA CANADA INC., Vancouver (CA)

(72) Inventors: Clare Maree Robertson, Vancouver (CA); Yuliya Victorivna Yaremenko, Vancouver (CA); Yu Wen Angela Huang, Vancouver (CA)

(73) Assignee: LULULEMON ATHLETICA CANADA INC., Vancouver (CA)

() Term: 15 Years

(21) Appl. No.: 29/918,240

(22) Filed: Nov. 27, 2023

Related U.S. Application Data

(60) Continuation of application No. 29/896,352, filed on Jul. 1, 2023, now Pat. No. Des. 1,010,979, which is a division of application No. 29/783,185, filed on May 11, 2021, now Pat. No. Des. 995,039.

CLAIM

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; and, FIG. 7 is a rear view thereof shown in an environment of use. The portions of the garment shown in broken lines in FIGS. 1-7 form no part of the claimed design. The broken line showing of the arms, torso, neck, and head in FIG. 7 is for the purpose of illustrating portions of the environmental structure and forms no part of the claimed design.

1 Claim, 7 Drawing Sheets
